SELF-PROPELLED LOADER

Louis J. Keller, Cyril N. Keller, and Clifford E. Melroe,
Gwinner, N. Dak., assignors to Melroe Manufacturing
Company, Gwinner, N. Dak., a corporation of North
Dakota

Filed July 25, 1962, Ser. No. 71,050

Term of patent 14 years

(Cl. D14—3)

FIG. 1

FIG. 2

FIG. 3

FIG. 4

FIG. 5

FIG. 6

FIG. 7

FIG. 1 is a left side perspective view of a self-propelled loader in lowered position showing our new design;

FIG. 2 is a left side perspective view of our loader in raised position;

FIG. 3 is a perspective view taken from the right rear side;

FIG. 4 is a perspective view taken from the right front side;

FIG. 5 is a top perspective view;

FIG. 6 is a front perspective view; and

FIG. 7 is a rear perspective view.

The dominant features of our design reside in the portions shown in full lines.

We claim:

The ornamental design for a self-propelled loader, as shown and described.
